Primary Examiner — Sandra Snapp*Assistant Examiner* — Anehita E. Oribabor(74) *Attorney, Agent, or Firm* — McKee, Voorhees & Sease, PLC(57) **CLAIM**

The ornamental design for a single device electrical junction box with side opening, as shown and described.

DESCRIPTION

FIG. 1 is a front perspective view of a single device electrical junction box with side opening;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left-side elevation view thereof; and,

FIG. 8 is a right-side elevation view thereof.

The dash-dash broken lines represent portions of the single device electrical junction box with side opening that form no part of the claimed design.
